By Hof. Dr. Julius Göttsche

UNITED STATES PATENT OFFICE

108,986

DESIGN FOR A GAME BOARD

Robert P. Schiffmann, Chicago, Ill.

Application February 8, 1938, Serial No. 74,968

Term of patent 14 years

To all whom it may concern:

Be it known that I, Robert P. Schiffmann, a citizen of the United States of America and a resident of Chicago, Cook County, Illinois, have invented a new, original, and ornamental Design for a Game Board, of which the following is a specification, reference being had to the accompanying drawing, forming a part thereof.

I claim:

The ornamental design for a game board substantially as shown.

ROBERT P. SCHIFFMANN.
